HAND STAPLER

Frank S. Boroughs, New York, N. Y., assignor to
 Arrow Fastener Co., Inc., Brooklyn, N. Y., a
 corporation of New York

Application March 25, 1948, Serial No. 17,040

14 Claims. (Cl. 1—49)

1

This invention relates to hand staplers.

An object of this invention is to provide a stapler of the character described, comprising a main frame, an anvil arm pivoted to the main frame at its rear end, a handle pivoted to the anvil arm at a point spaced from the pivotal connection between the anvil arm and the main frame, the pivot between the handle and the anvil arm having a limited movement relative to the main frame, a driver arm pivoted to the main frame, a staple driver blade adapted to be moved by the driver arm towards an anvil on the anvil arm, and links interconnecting the driver arm with the handle, the connection between the links and the handle being forwardly of the pivotal connection between the handle and the anvil arm, whereby the staple may be held in the hand, and the handle and main frame squeezed together, first causing the anvil arm to swing about its pivotal connection to the main frame for bringing the anvil upwardly toward the main frame and for thereafter causing the handle to rotate about its pivotal connection to the anvil arm for pulling down on the link to cause the driver arm to rotate about its pivotal connection to the main frame for causing the driver blade to press a staple against the anvil.

Another object of this invention is to provide a hand stapler of the character described, including a staple magazine case which may be inserted into the main frame through the front end of the main frame and a magazine lock arranged to be snapped onto the main frame for locking the magazine in position within the frame.

Yet a further object of this invention is to provide in a stapler of the character described, a pusher rod for the staple magazine, and a pusher rod lock attached to the rod and releasably engageable with the magazine.

Still a further object of this invention is to provide in a stapler of the character described, which shall be relatively inexpensive to manufacture, which shall be easy to assemble, which shall provide increased leverage to facilitate driving staples, which is so arranged that the device may be easily loaded with additional staples, and which shall yet be compact and practical and efficient to a high degree in use.

Other objects of this invention will in part be obvious and in part hereinafter pointed out.

The invention accordingly consists in the features of construction, combinations of elements, and arrangement of parts, which will be exemplified in the construction hereinafter described,

2

and of which the scope of invention will be indicated in the following claims.

In the accompanying drawings in which is shown various illustrative embodiments of this invention.

Fig. 1 is a front elevational view of a stapler embodying the invention, and showing the anvil arm in dot-dash line, after it has been swung about its pivot to the main frame upwardly towards the main frame;

Fig. 2 is a cross-sectional view taken on line 2—2 of Fig. 1;

Fig. 3 is a cross-sectional view taken on line 3—3 of Fig. 2;

Fig. 4 is a cross-sectional view taken on line 4—4 of Fig. 3;

Fig. 5 is a cross-sectional view taken on line 5—5 of Fig. 3;

Fig. 6 is a cross-sectional view taken on line 6—6 of Fig. 3;

Fig. 7 is a cross-sectional view taken on line 7—7 of Fig. 3 illustrating the main frame and part of staple magazine;

Fig. 8 is a cross-sectional view taken on line 8—8 of Fig. 3;

Fig. 9 is a cross-sectional view taken on line 9—9 of Fig. 3;

Fig. 10 is a cross-sectional view taken on line 10—10 of Fig. 3 and illustrating the staple magazine;

Fig. 11 is an end elevational view of the stapler shown in Fig. 1, and

Fig. 12 is a front elevational view similar to that shown in Fig. 1, with the anvil arm moved to a position bringing the anvil in contact with the underside of the outer end of the main frame.

Referring now in detail to the drawing, 10 designates a hand stapler embodying the invention for driving U-shaped staples of the usual

kind which may have a crown and two parallel legs. The stapler 10 comprises generally a main frame 11, to which is pivoted an anvil arm 12, as on pivot 13, and a handle 14, pivoted to the anvil arm 12 by means of a pivot pin 15 passing through aligned slots 16 in the main frame, and a driver arm 17 pivoted to the main frame on pivot 19 and adapted to drive a blade 20 for forcing staples on a staple magazine 21 towards an anvil 22 on the anvil arm 12, the driver arm 17 being connected to the handle 14 by means of a link 23.

The main frame 11 may be a metal stamping and comprises parallel side walls 25 interconnected by a top crown portion 26 running the full length of the frame. The crown 26 may be

curved as shown in Fig. 5 of the drawing. The side walls 25 are similar and symmetrically disposed. They are formed at the rear with downwardly and inwardly inclined edges 27 extending to a downwardly and rearwardly curved edge 28, from which extends rearwardly and downwardly inclined edges 29. Extending from the edges 29 are downwardly and forwardly curved edges 30, from which extend downwardly and inwardly inclined edges 31. Extending from the edges 31 are short horizontal edge portions 32, from which extend upwardly and forwardly inclined edges 33. Extending upwardly from the forward end of edges 33 are edges 34, from which there extends rearwardly horizontal edges 35. Extending upwardly from the edges 35 are edges 36 from which there extends forwardly horizontal edges 37. Extending upwardly from the edges 37 are square notches 38, each comprising a pair of parallel vertical edges 38a and a top horizontal edge 38b. The forward ends of edges 37 are disposed rearwardly of the forward ends of the top wall 26. Extending upwardly from the forward ends of edges 37 are vertical edges 40, terminating at 40a below the top wall 26. The edges 40 are formed with notches 41 for the purpose hereinafter appearing.

Extending forwardly from the upper ends of edges 40 are horizontal under edges 42. Extending upwardly from the forward end of edge 42 is a vertical edge 43, terminating somewhat below the top wall 26. Extending forwardly from the upper end of edge 43 is an edge 44, which extends to the forward edge 45 of the top wall 26.

The top wall 26 has a downwardly and forwardly inclined rear portion 26a, a central horizontal portion 26b and a downwardly inclined forward end portion 26c, as shown in Fig. 1 of the drawing. The side walls 25 (Fig. 7) are furthermore formed with inwardly punched detents 50, located centrally above the notches 38. Said side walls 25 are furthermore formed with small square openings 51, located just above the detents 50.

The side walls of the main frame 11 are furthermore formed with aligned openings 52, located below the rear portion 26a of the top wall 26 and just forwardly of the curved edges 28, to receive the pivot pin 19, which pivotally connects the driver arm 17 with the main frame.

The side walls of the main frame are furthermore formed with aligned openings 53 disposed just above the inclined edge 31, and substantially at the level of the curved edges 30. Said openings 53 are located somewhat more forwardly than the openings 52. Said openings receive the pivot pin 13 which pivotally connects the anvil arm 12 to the main frame.

Said side walls 25 are furthermore formed with slots 16, as stated above, through which the pivot pin 15 may move. The slots 16 are located substantially above the horizontal edge 32 of the side walls and project above and below the level of the openings 53. Said side walls 25 are furthermore formed with similar symmetrically disposed outwardly projecting substantially rectangular wall portions 55. Said wall portions 55 are located between the slots 16 and the vertical edges 36. Said recessed wall portions furthermore extend substantially from the level of the edges 36 to a point below the level of the openings 52. Said side walls 25 (Fig. 3) are furthermore formed just above the edges 32 with aligned rectangular slots 57, for the purpose hereinafter appearing.

The side walls 25 of the main frame 11 are

furthermore formed with a pair of parallel, inwardly pressed horizontal ribs 58 and 59 (Fig. 5). The ribs 58 and 59 of one wall are aligned with the ribs 58 and 59 of the other wall. The upper ribs 58 are preferably disposed more rearwardly than the lower ribs 59. The lower ribs 59 are located just below the level of the bottom edges 37, for the purpose hereinafter appearing. The upper ribs 58 are spaced above the ribs 59 by a predetermined vertical distance, as will appear hereinafter.

The anvil arm 12 comprises a pair of parallel symmetrical disposed side walls 60 interconnected by a bottom wall 61. The side walls 60 are formed with upper edges 62, parallel to the bottom wall 61. Said side walls 60 are formed with inwardly depressed portions 63 (Fig. 6) aligned with the outwardly depressed portions 55 of the main frame. Extending downwardly from the rear ends of the top edges 62 are inclined edges 64 (Fig. 3), which extend to the rear edge 64a of the bottom wall 61. Extending downwardly from the forward ends of edges 62 are edges 65 which are substantially aligned with the edges 33 of the side walls of the main frame. Extending forwardly from edges 65 are edges 66 somewhat downwardly inclined. At the forward end of edges 66 are downwardly extending notches 67 (Fig. 4). Forwardly of the notches 67 are upwardly extending projections 68, the upper edges of which are in alignment with the edges 66. Forwardly of the projections 68 is a continuous depressed edge 69 at the level of the bottom of the notches 67 and extending around the front end of an upwardly and forwardly curved wall 70 which interconnects the bottom wall 61 with the side wall 60. The side walls 60 are formed adjacent their rear ends with aligned openings 72 registering with the openings 53 and through which extends the pivot pin 13. The ends of the pin 13 may be riveted over so as to prevent side shifting of said pivot pin. The side walls 60 are furthermore formed, just rearwardly of the inwardly depressed portion 63 with aligned through openings 73 which are at the level of the openings 72, and through which the pivot pin 15 passes.

The bottom wall 61 is formed adjacent its rear edge 61a with a rivet opening 74 for the purpose hereinafter appearing. Said bottom wall is furthermore formed with a rivet hole 75 aligned with the projection 68, for the purpose hereinafter appearing.

Mounted on the front end of the anvil arm 12 is an anvil 76. Said anvil 76 may be formed with notches 77 to receive the projections 68. Said anvil rests on the bottom edges of the notches 67 and also on the edges 69. It may be formed with usual anvil grooves 78 for deflecting the arms or legs of the staple when the latter is driven in the manner hereinafter appearing. The anvil 76 is formed with a rivet hole 79 aligned with the rivet hole 75 to receive a rivet 80 which secures the anvil to the anvil arm.

For the purpose hereinafter appearing, there is attached to the underside of wall 61 of the anvil arm 12, a leaf spring 81. Said leaf spring is formed adjacent its rear end with a rivet hole 82 registering with the rivet hole 74. The leaf spring is attached to the bottom wall 61 by means of rivet 83 passing through the registering opening 74. Said leaf spring is made of spring stock and its function will be described hereinafter. The side walls of the main frame are interconnected by a bar 84, the ends of which are re-

ceived within the openings 57 and may be riveted over. The bar 84 is thus located below the leaf spring 81, and serves as a spacer to space the side walls 25 of the main frame and also as a tie rod to prevent spreading of the side walls of the main frame.

The handle may also be made as a stamping and is of U-shaped transverse cross-section. It comprises a pair of side walls 85 interconnected by a transverse curved bottom wall 86 extending the length of the handle. The bottom wall 86 is generally inclined forwardly and upwardly. Extending from the bottom wall 86 is an upwardly extending front wall 87 which likewise interconnects the side walls. Said walls 85 are formed with aligned top horizontal edges 88, from which extend downwardly and rearwardly inclined edges 89. Extending downwardly from the edges 88 are rear edges 90 which extend to the bottom wall.

Extending from the front ends of edges 88 are downwardly curved edges 91 located rearwardly of the outwardly depressed walls 55. Extending from the curved edges 91 are downwardly and forwardly curved edges 92, which are located below the lower ends of the outwardly depressed walls 55. Extending forwardly from the curved edges 92 are horizontal edges 93 from the forward ends of which extend downwardly curved edges 94, terminating at the front wall 87. Said side walls 85 (Fig. 9) are formed with aligned openings 96, registering with the openings 73 of the anvil arm, and through which pass the ends of the pivot pin 45. The ends of said pivot pin 45 may be riveted over to prevent side shift. Thus the pivotal pin 45 pivotally connects the anvil arm with the handle, and said pivot pin passes through from the slots 16 in the side walls 25 of the main frame 11.

It will be noted that the anvil arm 12 fits within the side walls of the main frame, whereas, the main frame fits between the side walls 85 of the handle. The side walls 85 of the handle are formed with aligned openings 99 located above the front end of the bottom wall 86 and substantially in alignment with the edges 55 for the purpose hereinafter appearing. Extending through the opening 99 is an abutment pin 99a, the ends of which are riveted over against the side walls 85 of the handle. Said pin 99a is located below the bottom wall 61 of the anvil arm. The free end of the leaf spring 81 contacts the underside of said pin 99a.

The driver arm 17 (Figs. 1 and 2) may also be made as a metal stamping if desired. The same comprises similar, symmetrically disposed side walls 100 interconnected by a top wall 101. The side walls 100 comprise rear parallel portions 102, central inwardly depressed parallel portions 103, and parallel portions 104 at the forward ends of the inwardly depressed portions 103 and front inwardly inclined walls 105, terminating in mutually contacting portions 106. The wall portions 104 are spaced apart, the same as are the wall portions 102. The top wall 101 extends from the rear end of the driver arm to the front ends of the parallel portions 104.

The inwardly inclined portions 105 taper in width toward the front mutually contacting ends 106. The wall portions 102 are formed with aligned openings 107 registering with the openings 52 and receiving the pivot pin 19 which inter-pivots the driver arm 17 to the main frame. It will be noted that the driver arm is located within the main frame between the side walls 25 thereof.

The front ends 106 of the driver arm, however, project forwardly beyond the front end of the top wall 26 and is located in the normal position of the staples just below the under edges 42.

The side walls 100 (Figs. 1 and 3) are formed with downwardly projecting ears 108 located somewhat rearwardly of vertical edges 38 and formed with through openings 109. Extending through the openings 109 is a pivot pin 110, the ends of which may be rounded over against the side wall portions 103. The link 23 interconnects the pins 110 and 99a (Fig. 6). Said link 23 comprises a top portion 111 from which extend similar symmetrically disposed side walls 112. The top wall 111 is located below the top wall 101 and above the pivot pin 110. The side walls 112 comprise side wall portions 113 disposed within the side wall portions 103 and formed with aligned through openings 114, through which the pivot pin 110 passes. The side wall portions 113 extend rearwardly of the ears 108 to a point aligned with the outwardly recessed walls 55. Extending outwardly from the side wall portions 113 are horizontal wall portions 115. Extending downwardly from the outer ends of wall portions 115 are downwardly extending wall portions 116 located within the recesses formed by the outwardly recessed walls 55 of the main frame. Extending inwardly from the lower ends of the wall portions 116 are shoulders 117 from which there extends forwardly and downwardly parallel wall portions 118 formed with through openings 119 registering with the openings 99 and receiving therethrough the pin 99a.

It will be noted that the length of the wall portions 116 is less than the length of the outwardly recessed wall portions 55 to permit up and down movement of the link as will appear hereinafter.

It will now be understood that the stapler may be held in the hand with four fingers wrapped about the underside of the handle, and the base of the thumb contacting the top of the rear end of the main frame 11.

Removably mounted within the main frame and locked therein in a manner hereinafter appearing, is a staple magazine 125. Said staple magazine 125 comprises a staple case and rail assembly 126, and a nose piece 127 attached to the forward end of the case and rail assembly. The case and rail assembly comprises a case 128 having a bottom wall 129, the lower surface of which is in the plane of the edges 37 (Fig. 12). Extending upwardly from the bottom wall 129 are parallel side walls 130. The bottom wall 129 rests on the lower ribs 59 (Fig. 1), which serve as a guide and support therefor. Said bottom wall is furthermore formed with a pair of upwardly depressed bosses 132 formed with rivet openings for the purpose hereinafter appearing.

Said bottom wall extends from a point aligned with edges 43 of the side walls 25 back beyond the curved edges 28 of said side walls. Extending inwardly from the upper ends of the side walls 130 are elongated flanges 133 (Figs. 6 and 8) adapted to contact the undersides of the ribs 58 (Fig. 5). Thus, the ribs 58 (Fig. 3) serve both as a guide and support for the staple magazine. At the front end of the case, the flanges 133 are formed with vertical upward extensions 134 (Fig. 8), from which there extends outward web portions 135, parallel to the flanges 133. Extending upwardly from walls 135 are walls 136 aligned with the side walls 130 of the magazine 125 (Fig. 8). The walls 136 may have forwardly and up-

wardly rear inclined edges 137 and a top horizontal edge 138 at the level of the edges 42 of the side walls of the main frame. Extending inwardly from the front ends of the side walls 136 are aligned vertical flanges 140. The front faces of said flanges are in the plane of the front edges of the bottom wall 129 and side walls 130. The lower edges of said flanges 140 are disposed above the walls 135. The side walls 130 and walls 136 substantially contact the inner sides of the walls 25 of the main frame. The bottom wall 129 is cut away to form a slot 129a registering with the square notches or slots 38 in the side walls of the main frame.

Attached to the case 128 is an inverted U-shaped rail member 141. The rail member 141 comprises a top wall 142, parallel to and spaced below the flanges 133 by somewhat more than the thickness or diameter of the staples to be used. Extending downwardly from the top wall 142 are parallel side walls 143, the lower edges of which contact the upper surface of bottom wall 129 of the magazine 125. The side walls 143 are spaced from the side walls 130, likewise by a distance somewhat greater than the diameter of the staples to be used.

The top wall 142 may be formed with punched out depressed tongues 145 riveted to the bosses 132 by rivets 146. The front end of the rail member 141 is flush with the front end of the case member 128, but extends rearwardly beyond the rear end of said case member. It will now be understood that staples 150 may ride on the rail 141 and between the rail and the case 128. The side walls of the rail member are formed at their lower edges with notches 151 disposed rearwardly of the case 128 for the purpose herein-after explained.

The nose member 127 (Figs. 2 and 3) comprises a front wall 155 formed with a central longitudinal slot 156. The lower edge of the nose piece is flush with the undersurface bottom wall 129. The upper edge of the front wall contacts the underside of the top wall 26 of the main frame. Extending rearwardly from the sides of the front wall are rearwardly stepped shoulders 157 contacting the flanges 140 of the case member 128, forming a space or slot 158 between said flanges and the front wall 155 for reception of a driving blade 20, as will appear hereinafter.

The upper ends of the shoulders 157 (Figs. 1 and 2) contact the edges 43 of the side walls of the main frame. Extending rearwardly from said shoulders are side walls 161 contacting the outer surfaces of the side walls 136 of the case member 128. The side walls 161 may be spot welded or otherwise attached to said side walls 136 for fixing the nose piece to the case member. The side walls 161 are formed with projections 163 received in the notches 41 in the front edges 40 of the side walls 25 of the main frame. The rear edges of the side walls 161 contact the front edges 40 of the side walls of the main frame, whereas, the upper edges of said side walls 161 contact the underedges 42 of the side walls of the main frame. Thus, the outer surfaces of the nose piece are flush with the outer surfaces of the side walls of the common frame. It will be noted that the front ends 166 of the drive arm 17 project through the slot 156. Said ends also project through an opening 165 in the drive blade. The slot 156 is elongated to permit movement of the front ends 166 of the drive arm through said slot, as the drive

arm is oscillated and the drive blade 20 is reciprocated.

Means is provided to lock the staple magazine in place within the main frame. To this end, there is provided a lock member 170 (Figs. 2 and 3) having a bottom wall 171 which fits into the slot 129a of the bottom wall 129 of the magazine case. Extending upwardly from the bottom wall 171, as shown in Fig. 7, are side walls 172 which fit within the slots 38 in the side walls of the frame. Extending upwardly from the side walls 172 are shoulders 173, from which there extends upwardly, arms 174. Arms 174 are formed with detents 175 which may snap into the detents 59 in the side walls 25 of the main frame. The side walls 174 are furthermore formed with inwardly punched prongs 176 which may snap into the openings 51 of the side walls 25. The lock member 170, thus prevents side shifting of the case lengthwise and serves to retain the staple magazine in operative position.

Mounted on the case and rail assembly 126 is a staple strip pusher 183. The same comprises a pusher rod 181 attached at its rear end to a pusher rod lock 182 and carrying a pusher member 183 adapted to engage the staple strip. The rod 181 may be of round stock and is riveted at its rear end to wall 185 of the pusher rod lock 182. Said lock 182 comprises a pair of similar symmetrically disposed side walls 186 (Fig. 10) interconnected by said wall 185. The walls 186 are formed at their forward ends with horizontally disposed slots 187 receiving the rear end of a top wall 142 of the rail 141. Portions of the walls 186 are received between the side walls 143 of the rail member 141. Said side walls 186 are formed with outwardly punched prongs 188 which are adapted to snap into the notches 151 in the side walls of the rail member. The prongs 188 are formed by slitting the side walls 186 along top and bottom parallel lines and at a line interconnecting the rear ends of said parallel lines, as shown in Fig. 3 of the drawing. The walls 186 tend to move away from each other so that the prongs 188 will enter the prongs or notches 151 to lock member 182 to the rail. When it is desired to release the pusher rod lock 182 from the rails, the walls 186 are pressed toward each other to disengage the prongs 188 from the notches 151.

Means is provided to limit inward movement of the walls 186 toward each other. To this end, each of said walls is cut along parallel top and bottom lines 189 to form therebetween a strap 190 which is depressed inwardly. When the walls 186 are pushed together, the straps 190 will contact each other to limit the inward movement of said walls. The rod 181 is riveted to the wall 185 as at 181, as shown in Fig. 3 of the drawing. On the rod 181 is a coil compression spring 193 interposed between the staple strip engaging member 183 and said wall 185 of member 182. Member 183 comprises a slider which slides on the top wall 142 of the rail member 141. The slider has a bottom wall 195 and a plurality of upstanding parallel walls 196, through which the rod passes. The spring 193 pushes against the slider 183, which in turn pushes the staple strip to the right, so that the foremost staple in the strip will be located below the blade 20.

When the handle 14 is initially squeezed, it lifts pin 15 to swing anvil arm 12 about pivot pin 13 from the position shown in Fig. 3 to the posi-

tion shown in Fig. 1. When the pin 15 reaches the upper end of the slot 16, further squeezing of the handle will cause rotation of the handle in a clockwise direction about the pivot pin 15, thereby causing the link 23 to be pulled downwardly for rotating the drive arm 17 in a clockwise direction about the pivot pin 19, thereby causing the driver blade 20 to move downwardly and expel the foremost staple in the staple magazine and press the same against the anvil 22. As the link is pulled down, the leaf spring 81 is tensioned thereby causing the parts to assume their normal position when the pressure is relieved, from the handle. The staples may be loaded from the rear by pressing the walls 186 of the rod lock 182 together and then pulling rearwardly to remove the pusher rod. The staple magazine may then be removed if desired by removing the lock 178, in which event the staple magazine may be pulled forwardly from the main frame.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. A stapler comprising a main frame formed with a slot, an anvil arm pivoted to the main frame, a pin on the anvil arm passing through said slot, a handle pivoted to said pin, a driver arm pivoted to the main frame, a link interconnecting the handle with the driver arm, a staple magazine within the main frame, and a driver blade slidably mounted at the forward end of the staple magazine and engaging said driver arm.

2. A hand stapler comprising a main frame, an anvil arm pivoted adjacent its rear end to said main frame, an anvil on the front end of said anvil arm, said main frame being formed with a slot spaced forwardly of the pivotal connection between the main frame and the anvil arm, a pin on said anvil arm passing through said slot, said slot permitting limited pivotal movement of said anvil arm relative to said main frame, a handle pivoted by means of said pin for rotation about the axis of said pin relative to said anvil arm, a driver arm pivoted adjacent its rear end to the main frame, and a link interconnecting the driver arm with the handle, the pivotal connection between the link and the driver arm being forwardly of the pivotal connection between the driver arm and the frame, and the pivotal connection between the link and the handle being disposed forwardly of the pin on which the handle is pivoted to the anvil arm, a staple magazine mounted on the main frame and disposed between the anvil arm and the driver arm, and a driver blade at the forward end of the driver arm.

3. A hand stapler comprising a main frame, an anvil arm pivoted adjacent its rear end to said main frame, an anvil on the front end of said anvil arm, said main frame being formed with a slot spaced forwardly of the pivotal connection between the main frame and the anvil arm, a pin on said anvil arm passing through said slot, said slot permitting limited pivotal movement of said anvil arm relative to said main frame, a handle

pivoted by means of said pin for rotation about the axis of said pin relative to said anvil arm, a driver arm pivoted adjacent its rear end to the main frame, and a link interconnecting the driver arm with the handle, the pivotal connection between the link and the driver arm being forwardly of the pivotal connection between the driver arm and the frame, and the pivotal connection between the link and the handle being disposed forwardly of the pin on which the handle is pivoted to the anvil arm, a staple magazine mounted on the main frame and disposed between the anvil arm and the driver arm, and a driver blade at the forward end of the driver arm, said main frame comprising a pair of parallel side walls interconnected by a top wall, one end of said anvil arm being disposed between said side walls, said handle comprising parallel side walls interconnected by a bottom wall, and the side walls of said main frame being disposed between the side walls of said handle.

4. A stapler comprising a main frame formed with a slot, an anvil arm pivoted to the main frame, a pin on the anvil arm passing through said slot, a handle pivoted to said pin, a driver arm pivoted to the main frame, a link interconnecting the handle with the driver arm, a staple magazine within the main frame, a driver blade at the forward end of the staple magazine and engaging said driver arm, and spring means adapted to be tensioned upon rotating said handle in one direction about the pin on which it is pivoted to the anvil arm for biasing said handle in an opposite direction when said spring is tensioned.

5. A hand stapler comprising a main frame, an anvil arm pivoted adjacent its rear end to said main frame, an anvil on the front end of said anvil arm, said main frame being formed with a slot spaced forwardly of the pivotal connection between the main frame and the anvil arm, a pin on said anvil arm passing through said slot, said slot permitting limited pivotal movement of said anvil arm relative to said main frame, a handle pivoted by means of said pin for rotation about the axis of said pin relative to said anvil arm, a driver arm pivoted adjacent its rear end to the main frame, and a link interconnecting the driver arm with the handle, the pivotal connection between the link and the driver arm being forwardly of the pivotal connection between the driver arm and the frame, and the pivotal connection between the link and the handle being disposed forwardly of the pin on which the handle is pivoted to the anvil arm, a staple magazine mounted on the main frame and disposed between the anvil arm and the driver arm, and a driver blade at the forward end of the driver arm, a leaf spring attached to the underside of the anvil arm and the free end of said leaf spring engaging the underside of the pivot by which the link is connected to the handle.

6. A hand stapler comprising a main frame having parallel side walls interconnected by a top wall, an anvil arm received between said side walls and pivoted adjacent its rear end to said side walls, an anvil on the forward end of the anvil arm, the side walls of said main frame being formed with aligned slots disposed forwardly of the pivotal connection between the anvil arm and the main frame, a pin extending through said anvil arm and engaging within said slots and extending therebeyond, a handle having parallel side walls interconnected by a bottom wall, the side walls of said main frame being received be-

11

tween the side walls of said handle, the pin on the anvil arm which passes through said slots engaging in bearing openings in the side walls of said handle, a pivot pin on the portion of the handle disposed forwardly of said slots, a driver arm disposed between the side walls of said main frame and above the anvil arm, and pivoted adjacent its rear end to the side walls of said main frame, a pivot pin carried by an intermediate portion of the driver arm, a link interconnecting the pivot pin on the intermediate portion of the driver arm with the last mentioned pivot pin on the handle, a staple magazine mounted between the side walls of said main frame and above the anvil arm, a driving blade at the forward end of the driver arm.

7. A hand stapler comprising a main frame having parallel side walls interconnected by a top wall, an anvil arm received between said side walls and pivoted adjacent its rear end to said side walls, an anvil on the forward end of the anvil arm, the side walls of said main frame being formed with aligned slots disposed forwardly of the pivotal connection between the anvil arm and the main frame, a pin extending through said anvil arm and engaging within said slots and extending therebeyond, a handle having parallel side walls interconnected by a bottom wall, the side walls of said main frame being received between the side walls of said handle, the pin on the anvil arm which passes through said slots engaging in bearing openings in the side walls of said handle, a pivot pin on the portion of the handle disposed forwardly of said slots, a driver arm disposed between the side walls of said main frame and above the anvil arm, and pivoted adjacent its rear end to the side walls of said main frame, a pivot pin carried by an intermediate portion of the driver arm, a link interconnecting the pivot pin on the intermediate portion of the driver arm with the last mentioned pivot pin on the handle, a staple magazine mounted between the side walls of said main frame, and above the anvil arm, a driving blade at the forward end of the driver arm, the last mentioned pivot pin on the handle being located beneath the driver arm, and a leaf spring attached at its rear end to the underside of the anvil arm, and the free end of said leaf spring engaging the underside of the last mentioned pivot pin on the handle.

8. A hand stapler comprising a main frame having parallel side walls interconnected by a top wall, an anvil arm received between said side walls and pivoted adjacent its rear end to said side walls, an anvil on the forward end of the anvil arm, the side walls of said main frame being formed with aligned slots disposed forwardly of the pivotal connection between the anvil arm and the main frame, a pin extending through said anvil arm and engaging within said slots and extending therebeyond, a handle having parallel side walls interconnected by a bottom wall, the side walls of said main frame being received between the side walls of said handle, the pin on the anvil arm which passes through said slots engaging in bearing openings in the side walls of said handle, a pivot pin on the portion of the handle disposed forwardly of said slots, a driver arm disposed between the side walls of said main frame and above the anvil arm, and pivoted adjacent its rear end to the side walls of said main frame, a pivot pin carried by an intermediate portion of the driver arm, a link interconnecting the pivot pin on the intermediate portion of the driver arm with the last mentioned pivot pin on the handle.

12

driver arm with the last mentioned pivot pin on the handle, a staple magazine mounted between the side walls of said main frame, and above the anvil arm, a driving blade at the forward end of the driver arm, the last mentioned pivot pin on the handle being located beneath the driver arm, and a leaf spring attached at its rear end to the underside of the anvil arm, and the free end of said leaf spring engaging the underside of the last mentioned pivot pin on the handle, said staple magazine comprising a case having a bottom wall, the side walls of said main frame having lower edges flush with the underside of said bottom wall, said side walls of the main frame being formed with aligned notches, the bottom wall of said case being formed with a cut-away registering with said notches in the side walls of said main frame, and a U-shaped magazine lock having a bottom portion received within said cut-away and upwardly extending portions received within said notches of the side walls of said main frame, and portions contacting the outer sides of the side walls of the main frame, and means to interengage said last mentioned portions of said magazine lock with the side walls of said main frame.

9. A hand stapler comprising a main frame having parallel side walls interconnected by a top wall, an anvil arm received between said side walls and pivoted adjacent its rear end to said side walls, an anvil on the forward end of the anvil arm, the side walls of said main frame being formed with aligned slots disposed forwardly of the pivotal connection between the anvil arm and the main frame, a pin extending through said anvil arm and engaging within said slots and extending therebeyond, a handle having parallel side walls interconnected by a bottom wall, the side walls of said main frame being received between the side walls of said handle, the pin on the anvil arm which passes through said slots engaging in bearing openings in the side walls of said handle, a pivot pin on the portion of the handle disposed forwardly of said slots, a driver arm disposed between the side walls of said main frame and above the anvil arm, and pivoted adjacent its rear end to the side walls of said main frame, a pivot pin carried by an intermediate portion of the driver arm, a link interconnecting the pivot pin on the intermediate portion of the driver arm with the last mentioned pivot pin on the handle, a staple magazine mounted between the side walls of said main frame, and above the anvil arm, a driving blade at the forward end of the driver arm, the last mentioned pivot pin on the handle being located beneath the driver arm, and a leaf spring attached at its rear end to the underside of the anvil arm, and the free end of said leaf spring engaging the underside of the last mentioned pivot pin on the handle, said staple magazine comprising a case having a bottom wall, the side walls of said main frame having lower edges flush with the underside of said bottom wall, said side walls of the main frame being formed with aligned notches, the bottom wall of said case being formed with a cut-away registering with said notches in the side walls of said main frame, and a U-shaped magazine lock having a bottom portion received within said cut-away and upwardly extending portions received within said notches of the side walls of said main frame, and portions contacting the outer sides of the side walls of the main frame, and means to interengage said last mentioned portions of said magazine lock with the side walls of said main frame.

13

lock with the side walls of said main frame, a nose piece on said staple magazine having top and rear edges engaging under edges and front edges of the side walls of said main frame, and guide means on the side walls of said main frame engaging top and bottom portions of said staple magazine.

10. A hand stapler comprising a main frame having parallel side walls interconnected by a top wall, an anvil arm received between said side walls and pivoted adjacent its rear end to said side walls, an anvil on the forward end of the anvil arm, the side walls of said main frame being formed with aligned slots disposed forwardly of the pivotal connection between the anvil arm and the main frame, a pin extending through said anvil arm and engaging within said slots and extending therebeyond, a handle having parallel side walls interconnected by a bottom wall, the side walls of said main frame being received between the side walls of said handle, the pin on the anvil arm which passes through said slots engaging in bearing openings in the side walls of said handle, a pivot pin on the portion of the handle disposed forwardly of said slots, a driver arm disposed between the side walls of said main frame and above the anvil arm, and pivoted adjacent its rear end to the side walls of said main frame, a pivot pin carried by an intermediate portion of the driver arm, a link interconnecting the pivot pin on the intermediate portion of the driver arm with the last mentioned pivot pin on the handle, a staple magazine mounted between the side walls of said main frame, and above the anvil arm, a driving blade at the forward end of the driver arm, the last mentioned pivot pin on the handle being located beneath the driver arm, and a leaf spring attached at its rear end to the underside of the anvil arm, and the free end of said leaf spring engaging the underside of the last mentioned pivot on the handle, said staple magazine comprising a case having a bottom wall, the side walls of said main frame having lower edges flush with the underside of said bottom wall, said side walls of the main frame being formed with aligned notches, the bottom wall of said case being formed with a cut-away registering with said notches in the side walls of said main frame, and a U-shaped magazine lock having a bottom portion received within said cut-away and upwardly extending portions received within said notches of the side walls of said main frame, and portions contacting the outer sides of the side walls of the main frame, and means to interengage said last mentioned portions of said magazine lock with the side walls of said main frame, a nose piece on said staple magazine having top and rear edges engaging under edges and front edges of the side walls of said main frame, and guide means on the side walls of said main frame engaging top and bottom portions of said staple magazine, said nose piece having a front piece formed with a longitudinal slot, said plate being formed with an opening receiving the forward end of said driver arm.

11. A hand stapler comprising a main frame having parallel side walls interconnected by a top wall, an anvil arm received between said side walls and pivoted adjacent its rear end to said side walls, an anvil on the forward end of the anvil arm, the side walls of said main frame being formed with aligned slots disposed forwardly of the pivotal connection between the anvil arm and the main frame, a pin extending through said anvil arm and engaging within said slots and ex-

14

tending therebeyond, a handle having parallel side walls interconnected by a bottom wall, the side walls of said main frame being received between the side walls of said handle, the pin on the anvil arm which passes through said slots engaging in bearing openings in the side walls of said handle, a pivot pin on the portion of the handle disposed forwardly of said slots, a driver arm disposed between the side walls of said main frame and above the anvil arm, and pivoted adjacent its rear end to the side walls of said main frame, a pivot pin carried by an intermediate portion of the driver arm, a link interconnecting the pivot pin on the intermediate portion of the driver arm with the last mentioned pivot pin on the handle, a staple magazine mounted between the side walls of said main frame, and above the anvil arm, a driving blade at the forward end of the driver arm, said driver arm comprising parallel side walls interconnected by a top wall, the front ends of said side walls of the driver arm being inclined toward each other, and the front ends of said driver arm contacting one another.

12. A hand stapler comprising a main frame having parallel side walls interconnected by a top wall, an anvil arm received between said side walls and pivoted adjacent its rear end to said side walls, an anvil on the forward end of the anvil arm, the side walls of said main frame being formed with aligned slots disposed forwardly of the pivotal connection between the anvil arm and the main frame, a pin extending through said anvil arm and engaging within said slots and extending therebeyond, a handle having parallel side walls interconnected by a bottom wall, the side walls of said main frame being received between the side walls of said handle, the pin on the anvil arm which passes through said slots engaging in bearing openings in the side walls of said handle, a pivot pin on the portion of the handle disposed forwardly of said slots, a driver arm disposed between the side walls of said main frame and above the anvil arm, and pivoted adjacent its rear end to the side walls of said main frame, a pivot pin carried by an intermediate portion of the driver arm, a link interconnecting the pivot pin on the intermediate portion of the driver arm with the last mentioned pivot pin on the handle, a staple magazine mounted between the side walls of said main frame, and above the anvil arm, a driving blade at the forward end of the driver arm, the side walls of said main frame having outwardly recessed portions, and said link having portions received within the recesses formed by said outwardly recessed portions, and said outwardly recessed portions being of greater length than the portions of the links received therein whereby to permit movement of said link.

13. A hand stapler comprising a main frame having parallel side walls interconnected by a top wall, an anvil arm received between said side walls and pivoted adjacent its rear end to said side walls, an anvil on the forward end of the anvil arm, the side walls of said main frame being formed with aligned slots disposed forwardly of the pivotal connection between the anvil arm and the main frame, a pin extending through said anvil arm and engaging within said slots and extending therebeyond, a handle having parallel side walls interconnected by a bottom wall, the side walls of said main frame being received between the side walls of said handle, the pin on the anvil arm which passes through said slots engaging in bearing openings in the side walls of said handle, a pivot pin on the portion of the handle disposed forwardly of said slots, a driver arm disposed between the side walls of said main frame and above the anvil arm, and pivoted adjacent its rear end to the side walls of said main frame, a pivot pin carried by an intermediate portion of the driver arm, a link interconnecting the pivot pin on the intermediate portion of the driver arm with the last mentioned pivot pin on the handle, a staple magazine mounted between the side walls of said main frame, and above the anvil arm, a driving blade at the forward end of the driver arm, the side walls of said main frame having outwardly recessed portions, and said link having portions received within the recesses formed by said outwardly recessed portions, and said outwardly recessed portions being of greater length than the portions of the links received therein whereby to permit movement of said link.

tion of the handle disposed forwardly of said slots, a driver arm disposed between the side walls of said main frame and above the anvil arm, and pivoted adjacent its rear end to the side walls of said main frame, a pivot pin carried by an intermediate portion of the driver arm, a link interconnecting the pivot pin on the intermediate portion of the driver arm with the last mentioned pivot pin on the handle, a staple magazine mounted between the side walls of said main frame, and above the anvil arm, a driving blade at the forward end of the driver arm, the front end of said handle being disposed rearwardly of the front end of the main frame and said driver arm projecting beyond the front end of the handle.

14. A hand stapler comprising a main frame, an anvil arm pivoted adjacent its rear end to said main frame, an anvil on the front end of said anvil arm, said main frame being formed with a slot spaced forwardly of the pivotal connection between the main frame and the anvil arm, a pin on said anvil arm passing through said slot, and permitting limited movement of said anvil arm relative to said main frame, a handle pivoted by means of said pin for rotation about the axis of said pin relative to said anvil arm, a driver arm pivoted adjacent its rear end to the main frame, and a link interconnecting the driver arm with the handle, the pivotal connection between the link and the driver arm being forwardly of the pivotal connection between the driver arm and the frame, and the pivotal connection between the link and the handle being disposed forwardly of the pin on which the handle is pivoted to the anvil arm, a staple magazine mounted on the main frame and disposed be-

tween the anvil arm and the driver arm and a driver blade at the forward end of the driver arm, said main frame comprising a pair of parallel side walls interconnected by a top wall, one end of said anvil arm being disposed between said side walls, said handle comprising parallel side walls interconnected by a bottom wall, and the side walls of said main frame being disposed between the side walls of said handle, said staple magazine comprising a case member having a bottom wall, the side walls of said main frame having lower edges flush with the underside of said bottom wall, said side walls of the main frame being formed with aligned notches, the bottom wall of said case being formed with a cut-away register with the notches in said frame side walls, and a U-shaped magazine lock having a bottom portion received within said cut-away, upwardly extending portions received in the notches of the frame side walls and portions contacting the outer sides of said frame side walls, and means to interengage said last mentioned portions of said magazine lock with the frame side walls.

FRANK S. BOROUGH.
